FIG. 3 is a rear, left, bottom perspective view of the battery box of FIG. 1.

FIG. 4 is a front, left, bottom perspective view of the battery box of FIG. 1.

FIG. 5 is a right side elevation view of the battery box of FIG. 1.

FIG. 6 is a left side elevation view of the battery box of FIG. 1.

FIG. 7 is a rear elevation view of the battery box of FIG. 1.

FIG. 8 is a front elevation view of the battery box of FIG. 1.

FIG. 9 is a top view of the battery box of FIG. 1.

FIG. 10 is a bottom view of the battery box of FIG. 1.

FIG. 11 is a front, left, top perspective view of a panel and footpads of the battery box of FIG. 1.

FIG. 12 is a rear, left, top perspective view of the panel and footpads of the battery box of FIG. 11.

FIG. 13 is a front, right, bottom perspective view of the panel and footpads of the battery box of FIG. 11.

FIG. 14 is a rear, right, bottom perspective view of the panel and footpads of the battery box of FIG. 11.

(Continued)

FIG. 15 is a left side elevation view of the panel and footpads of the battery box of FIG. 11.

FIG. 16 is a right side elevation view of the panel and footpads of the battery box of FIG. 11.

FIG. 17 is a front elevation view of the panel and footpads of the battery box of FIG. 11.

FIG. 18 is a rear elevation view of the panel and footpads of the battery box of FIG. 11.

FIG. 19 is a top view of the panel and footpads of the battery box of FIG. 11.

FIG. 20 is a bottom view of the panel and footpads of the battery box of FIG. 11.

FIG. 21 is a front, left, top perspective view of a panel of the battery box of FIG. 1.

FIG. 22 is a rear, left, top perspective view of the panel of the battery box of FIG. 21.

FIG. 23 is a front, right, bottom perspective view of the panel of the battery box of FIG. 21.

FIG. 24 is a rear, right, bottom perspective view of the panel of the battery box of FIG. 21.

FIG. 25 is a left side elevation view of the panel of the battery box of FIG. 21.

FIG. 26 is a right side elevation view of the panel of the battery box of FIG. 21.

FIG. 27 is a front elevation view of the panel of the battery box of FIG. 21.

FIG. 28 is a rear elevation view of the panel of the battery box of FIG. 21.

FIG. 29 is a top view of the panel of the battery box of FIG. 21.

FIG. 30 is a bottom view of the panel of the battery box of FIG. 21.

FIG. 31 is a front, left, top perspective view of a footpad of the battery box of FIG. 1.

FIG. 32 is a front, right, top perspective view of the footpad of the battery box of FIG. 31.

FIG. 33 is a rear, right, top perspective view of the footpad of the battery box of FIG. 31.

FIG. 34 is a rear, left, top perspective view of the footpad of the battery box of FIG. 31.

FIG. 35 is a front, left, bottom perspective view of the footpad of the battery box of FIG. 31.

FIG. 36 is a front, right, bottom perspective view of the footpad of the battery box of FIG. 31.

FIG. 37 is a rear, right, bottom perspective view of the footpad of the battery box of FIG. 31.

FIG. 38 is a rear, left, bottom perspective view of the footpad of the battery box of FIG. 31.

FIG. 39 is a left side elevation view of the footpad of the battery box of FIG. 31.

FIG. 40 is a right side elevation view of the footpad of the battery box of FIG. 31.

FIG. 41 is a front elevation view of the footpad of the battery box of FIG. 31.

FIG. 42 is a rear elevation view of the footpad of the battery box of FIG. 31.

FIG. 43 is a top view of the footpad of the battery box of FIG. 31; and,

FIG. 44 is a bottom view of the footpad of the battery box of FIG. 31.
